UNITED STATES PATENT OFFICE.

LOWE EMERSON, OF COLLEGE HILL, AND JOHN W. S. FISHER, OF CINCINNATI, OHIO.

VEHICLE-BOW.

SPECIFICATION forming part of Letters Patent No. 232,117, dated September 14, 1880.

Application filed August 28, 1878.

To all whom it may concern:

Be it known that we, LOWE EMERSON and JOHN W. S. FISHER, respectively of the town of College Hill and the city of Cincinnati, in the county of Hamilton and State of Ohio, have invented certain new and useful Improvements in Vehicle-Bows, of which the following is a specification.

Our invention relates to that class of bows for vehicle-tops which are covered with leather, mole-skin, tan-back, or other suitable material.

According to the ordinary method the leather which incases the bow, having been cut into the proper width and length, is then wrapped around the bow, and the two edges of the leather being brought together, they are sewed to each other. This method of applying the leather to the bows is objectionable, inasmuch as the raw rough edges of the leather at the seam protrude and form an unsightly rib upon the cover, being at once disagreeable to the eye and rough to the hand.

Our invention obviates this defect; and it consists in first stitching the material which is to form the cover, wrong side out, on a pattern of the same size and shape as the bow which is to be covered, then turning said material right side out in the act of withdrawing it from said pattern, and finally slipping the cover so sewed and turned onto the bow proper, thereby obtaining for the bow, as covered with leather, a handsome finish, the edges of the seam of the cover being within the latter and the surface being flush on both sides of the seam without any rib, so that a smooth seam at the juncture of the edges is presented on the exterior surface of the cover.

In the accompanying drawings, Figure 1 represents a view, in perspective, of a portion of a bow and cover embodying our invention. Fig. 2 represents a cross-section of the same.

A indicates a portion of the bow, for completeness of outfit provided with a slat-iron, B, the latter consisting of the eye *a* and shank *b*. The leather cover C incloses the bow. The

seam D, whereby the two longitudinal edges *d d'* of the cover are united, is smooth at the outside, the two protruding edges of the seam being within the cover and lying against the bow.

The method of preparing the cover and of applying it to the bow is as follows: From the leather blank a piece of the proper dimensions to form the cover is cut, which piece is placed around the bow, or a stick of similar size and shape, that surface which is to be the future outside of the cover being next to said bow or stick, and the edges sewed together, either by hand or machine. After the edges have been sewed together the cover is stripped off from the bow or stick by commencing at the larger end and turning it out, so that when it is entirely removed from the stick it will have been turned right side out. After the cover has been turned it is slipped upon the bow it is intended to cover, care being taken that the edges of the seam lie flat against the surface of the bow; or where a longitudinal groove has been provided in the bow the edges should lie in this groove. The bow is then employed in the vehicle-top in the customary modes.

Our invention gives the cover a beautiful finish, pleasing both to the eye and touch.

What we claim as new and of our invention is—

The within-described process of applying seamed flexible coverings to carriage-bows, which process consists in first stitching the material, wrong side out, on a pattern of the same size and shape as the bow, then turning said material inside out in the act of withdrawing it from the pattern, and finally slipping it onto the bow proper, substantially as and for the purposes specified.

LOWE EMERSON.
J. W. S. FISHER.
